POLARIZED ELECTROMAGNETIC RELAY

Filed Dec. 18, 1945

UNITED STATES PATENT OFFICE

2,483,658

POLARIZED ELECTROMAGNETIC RELAY

Charles Frank Miller, Frederick, Md., assignor to
Price Electric Corporation, Frederick, Md., a
corporation of Maryland

Application December 18, 1945, Serial No. 635,805

2 Claims. (Cl. 175—339)

1

This invention relates to magnet devices, generally of the polarized relay type.

This invention has utility when incorporated in a unit comprising a permanent magnet and an electromagnet, with a movable armature adapted to be differently thrown as the electromagnet current direction is reversed.

Referring to the drawings:

Fig. 1 is a side elevation, with parts broken away, of an embodiment of the invention in a switch device;

Fig. 2 is an end view of the device of Fig. 1, from the left;

Fig. 3 is a plan view of the device of Fig. 1, portions being removed or broken away;

Fig. 4 is a somewhat diagrammatic view of the magnet system with the electromagnet not under current and the armature in medial, or untilted position;

Fig. 5 is a view similar to Fig. 4, in which there is current for the electromagnet, which in looking down thereon is in a clockwise direction thru the winding coil, thereby to energize the system for the armature to tilt to the down or closed position at the left; and

Fig. 6 is a further view similar to Fig. 4, but here the energizing current thru the electromagnet, is in the opposite or reverse direction thru the winding coil, that is, counter-clockwise as looking down thereon, with the result that the electromagnet armature is tilted to have its closing or contact portion at the right of Fig. 6.

The magnets

A permanent magnet 1 is shown with a south or negative pole 2 and a positive or north pole 3.

An electromagnet is provided, which when not subjected to electric current flow, may have its base portion 4 operate as a keeper for the permanent magnet 1. Medially from the base 4 there rises a core 5, spaced from terminal parallel poles 6, 7, by an energizing coil or winding 8 about the core 5. Pins 9 in the core 5 rockably assemble medial dip portion 10 therewith, to have slightly upwardly pitched free ends 11, 12, of the armature in proximity to the electromagnet poles 6, 7. Rivets 13 in a short angle portion 14 which is integral with a finger 15, firmly lock the upstanding flat finger 15 to be upright centrally of the armature 10, 11, 12. When neutral or inactive, that is, with the ends 11, 12, each away from the poles 6, 7, it is desirable to have the member 15 extended in the axial direction of the core 5.

2

The assembly

A non-magnetic sheet metal mounting element or base is provided of a general channel form comprising parallel vertical side portions or cheeks 16, 17 as the flanges with a top horizontal web or bridge portion 18 providing a spacing connection between the flanges 16, 17. The portion 18 is not the full length of the flanges 16, 17, but, as the sides or flanges 16, 17, are against the U-shaped permanent magnet 1, 2, 3, the portion 18 is in the plane of and flush with the top of the poles 2, 3, and therebetween. From the clearance region between the poles 2, 3, a screw 19 extends upwardly thru the channel web 18 and base 4 to engage the core 5. The channel flanges 16, 17, have offset portions or ears 20 remote from and parallel to the web 18 with openings 21 to receive screws 22 for anchoring the unit.

16 The channel 16, 18, 17 has open ends and is sufficiently deeper than the magnet 1, 2, 3, to permit flanges 23 to enter in the plane of the ears 20. From the flanges 23 a riser portion or strip 24 is a web, closing the channel ends. The strip 24 25 extends upwardly beyond the channel 16, 18, 17, and has therethru screws 25 engaging the respective poles 6, 7, of the electromagnet. These three non-magnetic sheet metal frame portions now provide the means for assembly of the permanent 30 and temporary magnets into a unit.

The switches

The web portion 24 in the region of the poles 6, 7, has flanges 26, thereby providing vertically extending channels open toward each other, which 35 not only embrace the poles 6, 7, laterally, but extend upward and inward at legs 27 as beyond the web 24. Bolts 28, 29, thru switch block insulation 40 housings 30 and non-magnetic sheet metal H-braces 31, positively mount the housings 30. Protruding from each of the housings 30, and on 45 opposite sides of the finger 15, normally slightly spaced therefrom are plungers 32, yieldably outwardly positioned by springs 33. Thrusting of the 50 plunger 32 in one housing 30, is effective to operate one control when conductor lines 34, 35, from the coil 8 provide for current flow in one direction, say clockwise downward (Fig. 5). Before the 55 coil 8 is energized, the permanent magnet 3, 1, 2, has permanent magnet flux in the base 4 of density near saturation therefor in a positive direction from the portion 7 to the pole portion 6. Energizing of the coil 8 by current flow clockwise as looking down on the pole 5, establishes an electromagnetic flux into the base 4 tending to flow to-

ward the poles 7, 6. There is thus a tendency to increase the permeability of the base 4 toward the pole 7. The result is augmentation of the flux at the pole 7 thru the action of the temporary magnet supplementing the action of the permanent magnet. At the same time the flux from the energized pole 5, due to the clockwise direction of current flow in looking downward, in the base 4 toward the pole 6 is opposite to and accordingly tends to reduce the permeability of the base portion 4 region toward the pole 6. The net result is that the increased permeability of the base 4 toward the pole 7 brings about a tilt action for the armature to pull the pole 12 toward the pole 7 with the pole 11 thereby having greater spacing from the pole 6. Reverse direction of the current flow by other positioning of the reversing switch 36 from power supply lines 37, 38, brings about opposite rocking of the armature 10, 11, 12, to release the theretofore thrown plunger 32 for its automatic reset, and then to depress the other plunger 32 against its spring 33. This reversal or opposite housing 30 control, is effected by the current flow in the electromagnet upward or counterclockwise (Fig. 6). The counterclockwise direction of current flow in the coil 8, as looking down on the pole 5, increases the permeability of the base portion 4 toward the poles 2, 6, while decreasing the permeability of the base portion 4 from the pole 5 toward the poles 3, 7. Therefrom the armatured tilt is for the armature pole portion 11 to be toward the pole 6, with resultant greater spacing of the armature portion 12 from the pole 7. In the event the switch in the respective housings 30 be for changing from one circuit to another, there may be supply line 40 to be selectively connected from one direction electromagnet operation (Fig. 5). The companion or other housing 30, with its supply line 39 is responsive for the current flow to be changed from line 43 to the line 44. Instead of the lines 39, 40, or either thereof being supply, they may be service lines. The service supplied by the line 40 may be from a source thru a line 41, or a line 42. The mounting of the armature unit 10, 11, 12, including the finger 15 rigid therewith, as carried by the pole 5, while yieldable, is sufficiently stable that at all positions of non-current in the electromagnet 5, 6, 7, the finger 15 is clear of contacting the plungers 32 on opposite sides and close thereto.

The inactive medial or neutral tilt position for the rockable armature 10, 11, 12, with its upstanding arm 15, may be influenced to approximate central position between the microswitch housings 30, in response to the thrust of the plunger 32 as urged by its spring 33, at the electromagnet release therefor. The rockable armature may respond to being thrown by the electromagnet when the energizing of the electromagnet is such as different from that causing the last position throwing for the armature.

What is claimed and it is desired to secure by Letters Patent is:

1. A polarized relay comprising a central magnetic core, a substantially U-shaped sheet metal yoke of magnetic material made up of a central member rigidly joined at its center to a first end of the core and two parallel arms extending at

substantially right angles from opposite ends of the central member in the same direction as the core, the outer ends of the arms turned inwardly substantially coplanar with the second end of the core and parallel with the central member of the yoke, a flattened U-shaped rectangular polarizing permanent magnet of substantially the same length and width as the said central member and underlying and aligned therewith with the legs of the magnet in engagement with the central member adjacent the two arms of the yoke to oppositely magnetically polarize them, an energizing coil surrounding the core and closely enclosed by the sheet metal yoke member, and an armature pivotally mounted on the second end of the core with its outer ends overlying the ends of the yoke arms.

2. A polarized relay comprising a substantially U-shaped sheet metal yoke of magnetic material, said yoke embodying two parallel arms and a central member portion extending between the arms, said arms having inwardly turned ends remote from the yoke member portion, a flattened U-shaped rectangular polarizing permanent magnet of substantially the same length and width as said yoke central member portion, said magnet having legs in engagement with the yoke central member portion ends opposite the arms and in alignment with the arms, a magnetic core rigidly joined with the yoke central member portion to extend medially between and spaced from the arms, an energizing coil surrounding the core and closely enclosed by the yoke, and an armature rockably mounted on the core remote from the yoke central member portion, said armature having ends in proximity to and spaced from the inturned ends of the yoke arms when the coil is de-energized, and in relay operation said armature being rockable on the core as a fulcrum, to engage one yoke arm inturned end upon energization through the coil in one direction, and being rockable to engage the other yoke arm inturned end upon energization through the coil in the other direction.
